UNITED STATES PATENT OFFICE.

NATHAN SILVERSON, OF NEW YORK, N. Y.

DOOR-OPERATING APPARATUS.

1,405,691.

Specification of Letters Patent.

Patented Feb. 7, 1922.

Application filed May 31, 1921. Serial No. 473,726.

To all whom it may concern:

Be it known that I, NATHAN SILVERSON, a citizen of the United States, and a resident of New York, in the county of New 5 York and State of New York, have invented certain new and useful Improvements in a Door-Operating Apparatus, of which the following is a full, clear, and exact specification.

10 This invention relates to a class of devices adapted to be used in conjunction with doors.

My invention has for its object primarily to provide an apparatus designed to be employed on a door especially of a slidably movable class adapted to be used at the entrance of the elevator of a building and elsewhere so that the mechanism may be manually operated for causing the door to 15 move to an open position as well as being releasably held open if desired, besides being operable to cause the door to move to a closed releasably locked position at the entrance, in order to avoid the necessity of 20 the operator of the elevator to move the door to closed positions, thereby overcoming the liability of accidents occurring by the door being inadvertently left open following the departure of the elevator from a 25 landing. The invention consists essentially of providing on a door slidably movable across the entrance especially of an elevator and elsewhere of a locking bar with one or 30 more catches on its ends adapted to releasably engage one or more clips arranged on the walls of the entrance. This locking bar is yieldingly held so that when the door is 35 closed one of the catches will releasably engage one of the clips to lock the door, and by pressing the other end of the bar downwardly the catch will be disengaged to 40 enable the door to be moved to an open position. Associated with the locking bar is a spring actuated mechanism for causing 45 the door to be reversely moved to a closed position without requiring it to be manually closed, thereby avoiding the danger to person incident to the door being accidentally left open especially when the door is employed at the entrance to an elevator shaft. 50

A further object of the invention is to provide a door of a simple, efficient and durable construction which may be made in any suitable size.

55 With these and other objects in view the invention will be hereinafter more fully de-

scribed with reference to the accompanying drawings forming a part of this specification in which similar characters of reference indicate corresponding parts in all the 60 views, and will then be pointed out in the claims at the end of the description.

In the drawing, Figure 1 is a fragmentary view showing an elevation of a door and its entrance with one form of operating mechanism embodying my invention applied thereto.

Fig. 2 is a fragmentary sectional view, partly in detail, taken on the line 2-2 of Fig. 1.

Fig. 3 is a fragmentary view showing parts of the door in a partly open position and also showing part of the entrance with the operating mechanism, the view illustrating in dotted lines the position of the 75 mechanism when the door is open.

Fig. 4 is an enlarged sectional view, partly in detail, taken on the line 4-4 of Fig. 3, and

Fig. 5 is an enlarged fragmentary view 80 showing a reverse elevation, partly in detail, of parts of the mechanism.

The apparatus has a frame 10 including a plate 11 which may be of any suitable shape and size, though the form of plate 85 shown is substantially rectangular, and this plate may be bolted or otherwise fastened in a position crosswise of one face of a door, as 12, adapted to be slidably moved to open and closed positions at the entrance 13 leading to an elevator in a building or elsewhere. The door is preferably carried on a rod or bar, as 14, having its ends held to the walls 15, 16 below the top wall 17 of the entrance, and on the upper edge of the door are two spaced rollers, as 18 and 19, which are revolvable on the bar 14. In the entrance may also be a partition of an appropriate form, as 19^a, and on the side walls 15 and 16 of the entrance are provided suitable clips 20 and 21 which are on alinement with each other as well as being in opposed relation to the ends of the plate 11. The clip 21 may be of a well known form of an apertured plate which is countersunk in 100 the edge of the side wall 16 of the entrance 13 at the mouth of a recess, as 22, which is provided in this side wall, and the clip 20 is preferably in the form of an inverted hook, as shown. On the lower edge of the 105 end of the plate 11 of the frame 10 is a substantially L-shaped bar 23 having its lower

2
 arm extending from the plate so that its other arm is disposed upwardly across and in spaced relation to the plate. At the other end of the plate 11 is provided a bracket, as
 5 24, having a vertically disposed plate 25 secured to the plate 11 and the plate 25 may be of a length so that its upper end extends above the plate 11, and protruding from one of the edges of the plate 25 outwardly
 10 with respect to the plate 11 is a flange 26 having a lengthwise slot 27. Part of the upper end of the flange 26 may be bent rightangularly, as at 28.

In the slot 27 of the flange 26 of the plate
 15 25 and between the L-shaped bar 23 and the plate 11 of the frame 10 is a locking bar 29 which is slidably movable longitudinally as well as being movable in upwardly and downwardly directions. On the ends of the
 20 locking bar 29 are two catches 30 and 31, both of which may be somewhat of hook shapes provided by notching the lower and upper edge portions of the bar so that the catch or hook 31 is adapted to releasably engage the clip or plate 21 and so that the catch or hook 30 is adapted to releasably engage the clip or hook 20 of the entrance
 25 13. The locking bar 29 is disposed crosswise of the door and lengthwise of the plate 11 of the frame 10. This locking bar is also arranged whereby the catch 31 normally extends into the recess 22 of the wall 16 of the entrance 13 when the door is closed and so that the catch 30 will releasably engage the
 30 clip or hook 20 when the door is moved to open position. To the end part of the locking bar 29 adjacent to the catch 30 is held the lower end of a spring 32 having its upper end held to the bent end 28 of the flange
 35 26 of the bracket 24, and this spring is tensioned for serving to yieldingly hold this end of the locking bar in an upward direction with its other end being downwardly disposed into engagement with the clip or
 40 plate 21 for releasably locking the door in closed position.

When the door is unlocked by manually moving its spring controlled end downwardly for releasing the catch 31 from the
 45 clip 21 and with the manual moving of the door to an open position it is closed by two lever bars, as 33 and 34. One of the ends of these lever bars are pivoted together, at 35, and the bar 33 is proportionately longer than the bar 34 so that this pivot is at the upper rear corner of the door. The second end of the lever bar 34 is pivoted to a bracket 36 fixed to the partition 19 above the central part of the upper edge of the door. The lever bar 33 is disposed on a downward incline toward the catch 31 of the locking bar 29, and the second end of this lever bar extends across the forward portion as well as protruding below the locking bar. To the part of the lever bar 33

slightly above the locking bar 29 is pivoted one end of a link or short bar 37 having on its other end a pivot bolt or pin 38 with a head 39 on its free end. The bolt 38 is movably disposed through a slot 40 extending lengthwise of the plate 11 of the frame 10, and the end of the slot 40 in opposition to the catch 31 of the locking bar terminates with an opening 41 which is of greater diameter than the width of the slot and slightly larger than the head 39 of the bolt 38. The opening 41 serves to permit the head of the bolt 38 to be passed therethrough for being slidably disposed in the slot 40 without removing the plate 11 from the door, and this slot is of a length to permit the link 37 and the lever bar 33 to move the required distance across the door toward the clip 20 when the door is opened. The slot 40 is also of a length so that the opening 41 is arranged whereby the head 39 of the bolt 38 will not be accidentally separated from the plate 11 by passing through the opening when the door is closed. To part of the lever bar 33 spaced above the link 37 is held one end of a spiral spring 42 having its other end held to one end of a threaded adjusting rod or bolt, as 43, which is screwed through a threaded hole in the upper part of the flange 26 of the plate 25 of the frame 10. On the end of the rod 43 is a nut 44 adapted to be screwed into engagement with the flange 26 of the plate 25 for moving the rod 43 in a direction from the spring 42 for varying the tension of this spring which is normally tensioned to cause the lever bars 33 and 34 as well as the link 37 to move toward the catch 31 of the locking bar 29. With the unlocking of the catch 31 of the bar 29 and with the movement of the door to an open position, as above explained, the catch 30 of the locking bar 29 will engage the clip 20, as shown in dotted lines, Fig. 3, if it is desired that the door be held in an open position. The lever bar 33 will then be in the position also shown by the dotted lines in Fig. 3, and the spring 42 will be tensioned by being extensibly expanded so that when the locking bar 29 is released from the clip 20 the spring will cause reverse movements of the lever bars 33, 34 and link 37 for causing the door to be moved to a closed position as well as causing the catch 31 to lock with the clip 21 without requiring the door to be manually closed. The locking bar 29 is also of a length so that when the door is moved to open positions the catch 31 of the locking bar will be moved from a protruding position beyond the edge of the door to prevent the clothes of a person passing through the entrance from being caught in the catch.

In order to regulate the force of movement of the door when being closed, a bumper element, as 45, is provided. This bumper

element may be in the form of a commonly used type of pneumatic pump having a cylinder, as 46, with one of its ends being held, at 47, to the door under the catch 31 of the locking bar 29, and in the cylinder is a reciprocable piston 48 provided on one end of a rod 49, the other end of which extends beyond the cylinder. The second end of the rod 49 is pivoted, at 50, to the lower end of 10 the lever bar 33 so when the door is swung open the lever bar 33 will cause the rod and piston to move outwardly of the cylinder 46. With the closing of the door, as explained, the rod will be reversely moved in the cylinder 15 so that the air taken in the cylinder will be compressed for cushioning the force of the closing movement of the door, this being accomplished by regulating the resisting action of the bumper element 45 according to 20 the tension of the spring 42.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope 30 thereof.

Having thus described my invention, I claim as new and desire to secure by Letters Patent:—

1. The combination with a door slidably movable to open and closed positions across an entrance and the side walls of the entrance having alined clips, of a frame on the door, an upwardly and downwardly movable locking bar on the frame, catches 35 on the ends of the locking bar, one adapted to releasably engage one of the clips when the door is closed and the other catch being adapted to releasably engage the second clip when the door is open, a spring yieldingly 40 holding one end of the locking bar upwardly so that the catch at the other end of the bar and the cooperating clip on the entrance will be in normal engagement when the door is closed to allow the upwardly disposed end of 45 the bar to be pressed downwardly for releasing the engaged catch and clip, and mechanism associated with the locking bar, operable for causing the door to be moved to closed position following the manual opening 50 of the door.

2. The combination with a door slidably movable to open and closed positions across an entrance and the side walls of the entrance having alined clips, of a frame on the door, an upwardly and downwardly movable locking bar on the frame, catches on the 55 ends of the locking bar, one adapted to releasably engage one of the clips when the door is closed and the other catch being adapted to releasably engage the second clip

when the door is open, a spring yieldingly holding one end of the locking bar upwardly so that the catch at the other end of the bar and the cooperating clip on the entrance will be in normal engagement when the door is closed to allow the upwardly disposed end of the bar to be pressed downwardly for releasing the engaged catch and clip, mechanism associated with the locking bar, operable for causing the door to be moved to closed position following the manual opening of the door, and a bumper element on the door adapted to be actuated by the mechanism for cushioning the door during its closing movements. 70

3. The combination with a door slidably movable to open and closed positions across an entrance and one of the side walls of the entrance having a clip, of a frame on the door, an upwardly and downwardly movable locking bar on the frame, a catch on one of the ends of the locking bar, adapted to releasably engage the clip when the door is closed, a spring yieldingly holding one end of the locking bar upwardly so that the catch at the other end of the bar and the cooperating clip on the entrance will be in normal engagement when the door is closed to allow the upwardly disposed end of the bar to be pressed downwardly for releasing the engaged catch and clip, two lever bars having one of their ends pivoted together and the second end of one of the lever bars being pivoted to the top wall of the entrance, while the second end of the other lever bar is pivotally held to the locking bar, and a spring held to the frame of the door and held to one of the lever bars for yieldingly forcing the door to move to a closed position 95 when open. 100

4. The combination with a door slidably movable to open and closed positions across an entrance and one of the side walls of the entrance having a clip, of a frame on the door, an upwardly and downwardly movable locking bar on the frame, a catch on one of the ends of the locking bar, adapted to releasably engage one of the clips when the door is closed, a spring yieldingly holding one end of the locking bar upwardly so that the catch at the other end of the bar and the cooperating clip on the entrance will be in normal engagement when the door is closed to allow the upwardly disposed end of the bar to be pressed downwardly for releasing the engaged catch and clip, two lever bars having one of their ends pivoted together and the second end of one of the lever bars being pivoted to the top wall of the entrance, while the second end of the other lever bar is pivotally held to the locking bar, a spring held to the frame of the door and held to one of the lever bars for yieldingly forcing the door to move to a closed position when open, a device associated with the spring, 125 130

4
adjustable for varying the tension of the spring to regulate the force of movement of the door, and a bumper element on the door adapted to be actuated by the lever bars 5 for cushioning the door during its closing movements.

5. The combination with a door slidably movable to open and closed positions across an entrance and the side walls of the entrance having alined clips, of a frame on the door, an upwardly and downwardly movable locking bar on the frame, catches on the ends of the locking bar, one adapted to releasably engage one of the clips when the door is closed and the other catch being adapted to releasably engage the second clip when the door is open, a spring yieldingly holding one end of the locking bar upwardly so that the catch at the other end of the bar 20 and the cooperating clip on the entrance will be in normal engagement when the door is closed to allow the upwardly disposed end of the bar to be pressed downwardly for releasing the engaged catch and clip, two lever bars having one of their ends pivoted together and the second end of one of the lever bars being pivoted to the top wall of the entrance, while the second end of the other lever bar is pivotally held to the locking bar, and a spring held to the frame of the door and held to one of the lever bars for yieldingly forcing the door to move to a closed position when open.
6. The combination with a door slidably movable to open and closed positions across an entrance and the side walls of the entrance having alined clips, of a frame on the door, an upwardly and downwardly movable locking bar on the frame, catches on the ends of the locking bar, one adapted to releasably engage one of the clips when the door is closed and the other catch being adapted to releasably engage the second clip when the door is open, a spring yieldingly holding one end of the locking bar upwardly so that the catch at the other end of the bar 20 and the cooperating clip on the entrance will be in normal engagement when the door is closed to allow the upwardly disposed end of the bar to be pressed downwardly for releasing the engaged catch and clip, two lever bars having one of their ends pivoted together and the second end of one of the lever bars being pivoted to the top wall of the entrance, while the second end of the other lever bar is pivotally held to the locking bar, and a spring held to the frame of the door and held to one of the lever bars for yieldingly forcing the door to move to a closed position when open.

trance having alined clips, of a frame on the door, an upwardly and downwardly movable locking bar on the frame, catches on the ends of the locking bar, one adapted to 40 releasably engage one of the clips when the door is closed and the other catch being adapted to releasably engage the second clip when the door is open, a spring yieldingly holding one end of the locking bar upwardly so that the catch at the other end of the bar and the cooperating clip on the entrance will be in normal engagement when the door is closed to allow the upwardly disposed end of the bar to be pressed downwardly for releasing the engaged catch and clip, two lever bars having one of their ends pivoted together and the second end of one of the lever bars being pivoted to the top wall of the entrance, while the second end of the lever bar is pivotally held to the locking bar, a spring held to the frame of the door and held to one of the lever bars for yieldingly forcing the door to move to a closed position when open, a device associated with the spring, adjustable for varying the tension of the spring to regulate the force of movement of the door, and a bumper element on the door adapted to be actuated by the lever bars for cushioning the 65 door during its closing movements.

This specification signed and witnessed this 28th day of May, A. D. 1921.
